1 Claim

ABSTRACT OF THE DISCLOSURE

The present invention relates generally to improvements to hairpieces and more particularly to hairpieces having a novel arrangement of hair strands associated with a flexible sheet member. The embodiment of the invention disclosed herein includes a flexible or pliable sheet member having a predetermined contour and peripheral dimension conforming with a given surface area of a user's head. A plurality of adjacently positioned hairstrands are associated with the outer surface of the sheet member which, in the aggregate, afford the external appearance of natural hair. Each strand comprises a given length having sections penetrating the sheet at adjacently spaced intervals, the intermediate portion of each strand adhesively secured to the undersurface of the sheet member.

SUMMARY OF THE INVENTION

The present invention contemplates a hairpiece of improved, practical design which will overcome many of the inadequacies of hairpieces heretofore available. It has been a problem, for example, to provide hairpieces in which the hair strands may be parted and dressed much in the same manner as natural hair is combed and brushed. This is particularly significant in the design of hairpieces for men. The present invention contemplates a hairpiece in which each hair strand extends from a sheet of predetermined contour and dimension much in the same manner as the individual strands of hair extend from the human scalp.

More specifically, the present invention provides a lightweight hairpiece in which hair strands penetrate the above mentioned flexible sheet member at adjacently spaced intervals, and hence facilitates the ease with which the hair strands may be parted in any desired direction, and may be combed and brushed in a conventional manner.

It is a further object of the present invention to provide a hairpiece of the type referred to above which is readily washable, will not absorb body odors and will fit close to the user's head without the margin of the hair supporting sheet material being readily visible.

BRIEF DESCRIPTION OF THE DRAWING

The foregoing and other objects and advantages will be more apparent from the following detailed description when considered in connection with the accompanying drawing wherein:

FIG. 1 is a perspective view of a hairpiece of the type contemplated by the present invention;

FIG. 2 is a perspective view illustrating the manner in which the individual hair strands are inserted at closely spaced intervals through the thin, flexible sheet member;

2

FIG. 3 is an enlarged sectional view of a pair of strand lengths showing the manner in which these strands are initially inserted through the supporting sheet member;

FIG. 4 is a view similar to FIG. 3, showing adhesive material applied to the underside of the flexible sheet for securing the intermediate portions of each hair strand in flush engagement with the underside or surface of the flexible sheet member;

FIG. 5 is a view similar to FIG. 4, disclosing a sheet-like covering applied to the underside of the above mentioned sheet member after the intermediate portions of the hair strands have been adhesively secured in position;

FIG. 6 is a fragmentary perspective view showing the manner in which the outer margin or periphery of the combined sheets and adhesive illustrated in FIG. 5, may be stitched together;

FIG. 7 is a view similar to FIG. 6, disclosing the manner in which hair strands are hand knotted along the margin to conceal the stitching shown in FIG. 6;

FIG. 8 is a detailed perspective view of a hair strand formed with a hand knot of the type employed along the margin of the hairpiece as illustrated in FIG. 7; and,

FIG. 9 is a view similar to FIG. 5, illustrating an adhesive tab attached to the underside of the hairpiece for maintaining the hairpiece in proper position upon the head of a user.

DESCRIPTION OF THE PREFERRED EMBODIMENTS

Referring now to the drawing more in detail wherein like numerals have been employed to designate similar parts throughout the various figures, it will be seen that 35 a hairpiece which is representative of one embodiment of the present invention is designated generally by the numeral 10. The hairpiece 10 includes a sheet member 12 formed of thin, flexible material such as a suitable plastic which may be vacuum molded when subjected to heat. 40 In preparing the sheet 12 it is first necessary to employ a mold which conforms accurately to the contour of that area of the user's head which is to be covered by the hairpiece. Also, the peripheral dimension of the sheet 12 must conform to the size of the aforesaid area. By use 45 of a vacuum molding process, plastic sheet material 12 may be given a permanent or set contour identical with the head area to be covered.

Strands of hair 14 may now be applied to the sheet 12 as indicated in FIG. 3. Each of the strands 14 comprise a given length of hair having opposite sections 16 thereof penetrating the sheet at closely spaced intervals. These strand sections 16 extend outwardly from the pliable sheet or base 12 and an intermediate portion 18 of each strand underlies the sheet 12. When sufficient hair strands have thus been applied to the sheet member 12 so as to afford, in the aggregate, the external appearance of a full body of natural hair, the intermediate portions 18 may be secured in flush association with the 55 undersurface of the sheet member 12 by the use of a thin layer of suitable soft type adhesive or glue 20. A second thin, flexible, preformed sheet 22 may now be applied to the underside of the sheet member 12. The sheet member 22 like the sheet member 12, is preferably 60 formed of suitable waterproof plastic material which may 65

be contoured in conformity with a given surface area of a user's head in the manner previously described with respect to the sheet member 12. The sheet member 22 provides a soft, skin-like surface which may be comfortably worn by the user.

The peripheral or outer margin of the combined sheet members 12 and 22 may be secured together by conventional stitches 24, as illustrated in FIG. 6. In order to conceal the stitches 24, and also to provide a natural appearing hairline along the margins of the combined sheets, additional strands of hair 16a are attached or knotted to said margin as indicated. In FIG. 8 the type of hand knot is illustrated which is employed to secure the strands 16a along the margin of the combined sheets. In FIG. 7 the adjacent pairs of strand sections 16a are indicated as extending upwardly from the sheet 12. In instances where desirable, the hand knot may be made with the hairstrands extending from the undersurface of the sheet member 22. The manner in which the hand knot is applied may depend upon the environment in which the hairpiece is to be used.

In conventional hairpieces, it has been common practice to employ binding tape or ribbon along the margin of the hairpiece. The present invention avoids the necessity of using conventional binding tape. As mentioned above, the presence of the hand knotted strands 16a not only serves to conceal the presence of the stitches 24, but also assures the appearance of a very natural character to the hairline. In this connection, it is to be noted that no portion of the margin of the combined sheet members projects beyond the hairline, hence providing the above-mentioned natural appearance.

It has heretofore been common practice in some instances to employ a plurality of hand-knotted hair strands over the entire surface of a hairpiece sheet. Hair strands thus applied do not readily lend themselves to be directed in any desired direction by combining or brushing. This is due to the fact that the hand-knotted strands have a tendency to incline in a set direction as indicated in FIG. 8. The present invention avoids this difficulty by having each single strand section penetrate the sheet 12 in closely spaced relation with the next adjacent strand section. This arrangement is to be clearly distinguished from the prior hairpieces employing only hand knotted strands wherein two hair strands project from the same aperture in the hairpiece sheet. Although the hairpiece sheets are preformed as described above, so as to conform in contour with the contour of the user's head, it has been found practical to employ additional means to assure permanent positioning and attachment of the hairpiece. Thus in FIG. 9 it will be seen that a thin section of sheet material 26 is adhesively secured to the underside of the sheet member 22. The sheet members or patches 26 may be in the nature of conventional pressure-sensitive tape which has a coating of adhesive on both sides. Thus the underside of the member 26, when pressed against the user's scalp, will serve to effectively counteract any tendency for the hairpiece to become dislodged. In instances where necessary, several of the patches or strips 26 may be used in association with a given hairpiece. In fact, experience has shown that hairpieces constructed in accordance with the teachings of the present invention will be secured against dislodgement even when the wearer is enjoying a swim. The pliable, light-weight, waterproof nature of the hairpiece sheet, together with the adhesive patches, assure permanency in attachment and natural appearance free from an unsightly hairline.

From the foregoing it will be apparent that the present invention contemplates a hairpiece of very practical construction which will afford an unusually natural appearance to the wearer. Having the individual strand sections extending through the flexible hairpiece sheet in closely spaced relation with the other hair strand sections, enables the hair strands to be parted and set in

any desired direction. It is preferable for the hairpiece sheet 12 to have a flesh-like color, so that strands of hair projecting therefrom afford an appearance substantially identical with strands of hair projecting from the human scalp. With the bight portion of each U-shaped strand of hair secured to the underside of the sheet 12 by a suitable soft pliable adhesive or glue, the hair strands may be combed or brushed vigorously without any danger of strands being pulled away from the sheet. By simply stitching the margins of the combined sheets and then applying hand-knotted hair strands thereto, a hairline of natural appearance is obtained. Heretofore it has been common practice to bind the margins of a hairpiece sheet with binding tape or ribbon, and in such instances the resulting hairline is quite unnatural in appearance. As above-mentioned, the sheets 12 and 22 may be formed from soft, pliable, thin plastic sheet material which is waterproof and hence permits washing in water or by the use of conventional shampoo material. Thin, surgical, transparent pressure-sensitive tape may be used for the patches 26. Such tape is very soft and flexible, readily conformable to the shape of the wearer's head. In fact, the sheet material is extremely light in weight and has the soft feel of a human scalp. The above-mentioned sheet material will not disintegrate or rot from proximity to normal body acids, such as result from perspiration. Furthermore, the sheet material will not absorb body odors, as distinguished from porous sheet material such as cloth which has heretofore been used. The average weight of a hairpiece may be approximately 2½ oz., the hair weighing approximately 2 oz., and the sheet material ½ oz. The plastic sheet material may be vacuum formed under temperature conditions varying from 300-500°. By this procedure the sheet material is given a permanent set which will not vary throughout the period of use of the hairpiece. It has been found practical in some instances to form the sheet 22 of stiffer material than the sheet 12.

It should be appreciated that while FIG. 7, discloses only a few hand knotted strands along the margin of the hairpiece for the purpose of more clearly illustrating the nature of the hand knot, the completed hairpiece incorporates a plurality of adjacently positioned hand knotted strands along the exposed edges of the strand supporting sheets, as well as along the area spaced inwardly from said edge to effect concealment of the stitches. The environment in which the margin of the hairpiece is to be used, will determine the particular placement of the strand knots. In FIGS. 7 and 8, for example, the strand knot is such as to urge or direct the strand extremities to the right as viewed in these figures. In certain instances the knotting needle may be inserted from the topside of the sheet members, whereas in other instances the needle may be inserted from the bottom surface thereof. Thus, the formation of a sufficient number of the strand knots will assure proper setting of the hair strands, concealment of the stitching, and the assurance of a hairline which is very natural in appearance. It is also of importance to note that in the area of the hairpiece where the hair strands are to be parted, it is essential that the hair strands be applied in the manner specifically illustrated in FIGS. 2-5, inclusive.

What is claimed is:

1. A hairpiece comprising a first thin, flexible sheet member of premolded plastic material having a predetermined contour and peripheral dimensions conforming substantially with a given surface area of a user's head, a plurality of adjacently positioned hair strands extending from the outer surface of said sheet member so as to afford in the aggregate the appearance of natural hair, each strand comprising a given length having sections thereof penetrating said first sheet member at adjacently spaced intervals and extending outward from said sheet

member, the intermediate portion of each of said strands underlying said first sheet member, said first flexible sheet member providing the sole means from which the hair strands extend, adhesive means securing the intermediate portions of said strand in flush association with the undersurface of said first sheet member, a second relatively thin, flexible plastic sheet member preformed to the contour of the user's scalp and superimposing the intermediate strand portions, the outer margins of said first and second sheet members being stitched together, and a plurality of adjacently spaced hair strands knotted to said margin and so disposed as to effectively conceal the aforesaid stitches.
